AIR CIRCULATING SYSTEM FOR DRIERS

Alpheus O. Hurxthal, Wyncote, Pa., assignor to
Proctor & Schwartz, Incorporated, Philadelphia, Pa., a corporation of Pennsylvania

Application September 12, 1939, Serial No. 294,526

1 Claim. (Cl. 34—212)

This invention relates to air circulating systems for driers. The object of the present invention is to provide a special type of air circulation in connection with a drier where there must be no recirculation of the air over the heating coils but at the same time there must be recirculation of the air through the material being dried.

In the present instance, the invention as disclosed as being applied to that type of drier wherein the material undergoing treatment is transported through a suitable drying chamber containing conditioned air in circulation, i. e. air of regulated temperature and/or humidity.

In the prior art driers of the above noted type, the drying air is normally circulated within the drying chamber, transversely thereof, in a manner to make repeated contacts with the material being advanced through the drying chamber, and through a circulating compartment at one side of the drying chamber wherein the air passes and makes contact with suitable temperature regulating and/or humidifying units in its course of circulation, between its successive contacts with the material in the drying chamber.

In some instances, contact of the circulating air with the conditioning units after initial contact of the air with the material being treated is undesirable because of dust or gaseous matters given off by some materials becoming entrained in the drying air, and because such gases or solid matters should not be permitted to come into contact with the heating or other conditioning units in the drier. It is the object of the present invention to provide an efficient apparatus of simple compact construction for creating and maintaining an improved type of air circulation to satisfy the above noted requirements.

In the accompanying drawings:

Fig. 1 is a diagrammatic plan view of a multi-section drier embodying the novel features of the present invention;

Fig. 2 is a transverse sectional elevation taken on the line 2—2, Fig. 1; and

Fig. 3 is an enlarged longitudinal sectional view of one of the air circulating devices employed for producing and maintaining the improved circulation in accordance with the principles of the present invention.

As shown in Fig. 1, the apparatus includes a drying chamber A which preferably is composed of a plurality of sections A¹, A², A³, A⁴, A⁵, for example. Each section extends transversely of the drier as a whole between the side walls 1 and 2

thereof, the roof 3, and a sub-floor 4 which is spaced above and parallel to the bottom 5 of the drier.

Adapted to travel longitudinally through the drying chamber A, successively through the adjacently disposed sections thereof, is a conveyer of a horizontal endless belt type, the carrying run 6 of which is disposed in a plane intermediate the roof 3 and sub-flooring 4, while the return run 7 travels through the space 8 formed between the flooring 4 and the bottom 5. The various sections of the drying chamber A are separated by transversely extending partitions 10 in which are formed openings 11 for passage of the conveyer run 6.

At one side of and spaced laterally from each or any predetermined number of the sections A¹, A², etc. is an air conditioning chamber 12, in which is mounted a suitable heating and/or humidifying unit 13. Admission of air to the upper end of each conditioning chamber 12 is controlled by an adjustable damper 14, whereby predetermined quantities of extraneous air may pass into the conditioning chamber from the outside atmosphere and through the conditioning unit 13 for initial regulation of temperature and/or humidity for subsequent entrance into the drying chamber A.

In a compartment 15 disposed intermediate the drying chamber A and the air conditioning chamber 12, for each of the sections A¹, A², etc. thereof respectively, is an air impeller 16. As shown in Fig. 3, each impeller 16 comprises a rotor 17 composed of a pair of axially spaced concentric frusto-conical annular end plates 18, between which impeller blades 19, 19 extend in a general axial direction.

Intermediate the opposite end plates 18, 18 of each rotor 17, the impeller 16 is provided with a transversely extending disc 20 which divides the impeller blades 19 into relatively short and long sections 19^a and 19^b respectively. The disc 20 is supported by a suitable hub 21 in which one end of a supporting and driving shaft for the rotor 17 is suitably secured.

The shaft 22 of each rotor 17, as shown in Fig. 2, extends completely through the conditioning chamber 12 to and through the outside wall 9 of the conditioning chamber 12 to a driving motor 24 which is secured to the wall 9, outside the drier. If desired, a bearing 25 may be provided for the shaft 22 adjacent the inner wall 26 of the conditioning chamber 12.

Secured to the wall 26, and affording communication between the conditioning chamber

12 and the end of the rotor 17 at that side of the disc 20 in which the shorter blades 19^a are located, is a frusto-conical duct 27; and at the opposite side of the disc 20 is a similar frusto-conical duct 28 which affords communication between the second end of the rotor 17 and that portion of the drying chamber A lying intermediate the carrying run 6 of the conveyer and the sub-floor 4 of the drier.

As each impeller 17 is rotated by its motor 24, air is simultaneously drawn from the conditioning chamber 12, through the duct 27 by the blades 19^a, and from the lower portion 29 of the drying chamber A, through the duct 28 by the blades 19^b, and is delivered radially outward into a casing 30 which surrounds the rotor 17, within the intermediate compartment 15. The drawn air is conducted from the casing 30 to an opening 32 in the upper portion of the drying chamber A by a duct 31, in which the fresh extraneous air from the conditioning chamber 12 is thoroughly mixed with the air simultaneously drawn from the drying chamber A the air passing through the inlet opening 32 being suitably deflected, to pass downwardly in the drying chamber A, by suitable louvers 33.

As indicated by the arrows in Fig. 2, the air initially enters the drying chamber A, through the regulating damper 14 in the upper end of the conditioning chamber 12, under the impetus of the impeller 16, by which the air is drawn downwardly through the conditioning chamber 12 and then moved upwardly into the upper portion of the drying chamber A, the air being suitably conditioned enroute through the chamber 12 before it enters the drying chamber A.

The air is also circulated transversely of the drying chamber A by the rotor 17, by being drawn into the axial inlet 28 of the impeller 16 from the lower portion 29 of the drying chamber A, and driven outwardly from the peripheral discharge of the rotor 17 of the impeller into the impeller casing 30 from which the air passes through the duct 31 and opening 32 into the upper portion of the drying chamber A, solely.

The drying air, after its initial conditioning in the chamber 12, and after its initial contact with the material supported by the conveyer run 6, never again makes contact with the conditioning unit 13.

As freshly conditioned air is continuously supplied through the regulating damper 14, and mixed, in the casing 30 and duct 31 with the air in circulation within the drier, a suitable quantity of moist air is exhausted from said circulation, through an exhaust duct 34 communicating with the lower portion 29 of the drying chamber A, under the impetus of a suitable exhaust fan 35 which is driven by an independent motor 36, or equivalent means. If desired, there may be an exhaust fan 35 for each of the various sections of the drying chamber. However, under normal conditions, a single fan 35 may be operated efficiently to exhaust a sufficient quantity of moist air from the drying chamber A as a whole.

As shown in Fig. 1, the sections A¹ and A² are provided with individual dampers 14^a and 14^b respectively. The sections A³, A⁴, and A⁵, however, are supplied with fresh extraneous air from a single damper 14^c which communicates with a single elongated conditioning chamber 12^a common to all three sections A³, A⁴, and A⁵.

Each section may be provided with individual automatic temperature and humidity regulating 75

devices of any of the types commonly known to the art, such, for example, as wet and dry bulbs, whereby the units 13 may be automatically controlled as well as the dampers 14^a, 14^b, and 14^c which regulate the quantities of air admitted to the respective conditioning chambers.

In some instances, it may be desirable to pass the air in circulation from one section to another, with or without adding fresh extraneous air thereto, in which case the dampers 14^a, 14^b and 14^c may be selectively closed or opened and each or any desired number of the partitions 10, between the various sections, may be provided with an adjustable gate 37 which is hingedly mounted at one of its ends to the partition 10 in an opening 38 formed in said partition, said gate 37 normally lying in the plane of the partition 10 and being adapted to be swung to either side thereof at an angle thereto, as shown in broken lines in Fig. 1, for controlling the passage of air from one section to the next, through an opening 38 formed in the partition 10 between the carrying run 6 of the conveyer and the sub-flooring 4 of the drier.

From the above it will be clear that in a device constructed and operated as described, each section of the drier may have its own independent properly proportioned heating unit and control, by which similar or differential temperatures best suited to the specific drying problem at hand may be obtained and maintained throughout the length of the drier. Likewise the dampers for the extraneous air admitted to the conditioning chambers may be manually or automatically controlled independently for regulating the desired amount of air to be delivered to the drying chamber.

Furthermore, the air may be initially heated in one end of the drier and continuously mixed with freshly conditioned air and then circulated through the drying chamber from one section to the next in suitable quantities, by regulating the gates 31, whereby the air may be caused to move in a spiral path through the drying chamber A, from one section to the next thereof, the moist air being exhausted from the opposite end of the drier by any suitable means such as a fan of suitable capacity having a construction similar to the exhaust fan 35, or an equivalent structure. Under such conditions, obviously, the section of the drying chamber nearest the discharge end for the material would be of the highest temperature and of the lowest moisture content.

I claim:

A drier comprising a drying chamber devoid of any air conditioning means, means for circulating air solely within said drying chamber in a course transversely thereof, a second chamber provided with air conditioning means, means for moving unconditioned air from outside said drier into said second chamber for initial conditioning and for moving the initially conditioned air from said second chamber into the circulation of air in said drying chamber, an air-intercepting gate in said drying chamber for selectively diverting the air circulating solely therein and transversely thereof in either direction longitudinally of said chamber from one portion of said transverse course of circulation into an adjacent portion of said transverse course of circulation solely within said drying chamber, and means for discharging said circulating air to waste outside said drier.

ALPHEUS O. HURXTHAL.
